(57) **CLAIM**

The ornamental design for an electrical connector, as shown.

DESCRIPTION

The present application is related to U.S. application Ser. No. 29/381,569, filed on Dec. 21, 2010.

FIG. 1 is a front elevation view of an electrical connector showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front and right side perspective view thereof;

FIG. 8 is a top plan view of the electrical connector mounted in a use position and wiring to be inserted therein;

FIG. 9 is a right side elevation view of the FIG. 8 configuration; and,

FIG. 10 is a top, front and right side perspective view of the FIG. 8 configuration.

The broken lines of FIGS. 8-10 depict environment of the connector and constitute unclaimed subject matter and forms no part of the claimed design.

The article is an electrical connector which is mounted on a circuit board (see FIGS. 8-10) so as to electrically connect a cable which is inserted from an opening provided at the front side of a connector main body with the circuit board.
